ATTORNEYS

UNITED STATES PATENT OFFICE.

ISIDOR SOMMERFIELD, OF CHICAGO, ILLINOIS.

SELF-ADJUSTING ARCH SUPPORT.

Application filed October 23, 1922. Serial No. 596,277.

To all whom it may concern:

Be it known that I, ISIDOR SOMMERFIELD, a citizen of the United States, and a resident of Chicago, in the county of Cook and State of Illinois, have invented a new and useful Improvement in Self-Adjusting Arch Supports, of which the following is a full, clear, and exact description.

My invention relates to improvements in self adjusting arch supports, and it consists in the combinations, constructions, and arrangements herein described and claimed.

An object of my invention is to provide an arch support of the character described in which means is provided for adjustably supporting the inner and outer longitudinal arches independently of one another.

A further object of my invention is to provide an arch support of the character described that is capable of adjusting itself to the peculiar contour of the patient's foot. This improvement is of utmost importance since there are four arches to the foot, any one or more of which may be abnormal and cause discomfiture.

A further object of my invention is to provide an arch support of the character described that is composed of a single piece of resilient metal which is adapted to be inserted between the insole and the outer sole of the shoe of the wearer.

A further object of my invention is to provide an arch support of the character described that is normally substantially flat until cooperating portions thereof are locked to one another to occasion a resilient arch intermediate the support, which operation is performed prior to applying the arch support to the shoe.

Other objects and advantages will appear in the following specification, and the novel features of the invention will be particularly pointed out in the appended claims.

My invention is illustrated in the accompanying drawings, forming part of this application, in which —

Figure 1 is a top plan view of my improved arch support in a substantially flat condition,

Figure 2 is a sectional view of my arch support after it is applied to a shoe,

Figure 3 is a side elevation of the arch support seen in Figure 2, and

Figure 4 is a perspective view of my improved arch support immediately prior to its application to a shoe.

In carrying out my invention, I make use of the ordinary type of shoe 1 having an insole 2 and an outer sole 3. As in the case of many arch supports and reenforcing devices, I insert my self-adjusting arch support between the soles 2 and 3 of the shoe 1.

My arch support comprises a metal member 4 composed of a fine quality of spring steel. The member 4 is stamped substantially the shape shown in Figure 1 from the flat sheeting and is pointed at one end 5 and substantially blunt at the opposite end 6. There is an opening 7 disposed longitudinally through the member 4, and a slot 8 through the relatively blunt end 6 communicating with the opening 7. The slot 8 is substantially parallel with the longitudinal axis of the member 4.

A pair of small openings 9 are provided in the end 5, and a pair of sharp upturned integral lug portions 10 are provided at the end 6 of the member 4. These lug portions 10 are formed by shearing and upturning a portion of the member 4.

The body member 4 is provided at the end 6 thereof with a slot 11 adjacent the slot 8 and with an integral hook portion 12 adjacent the opposite edge of the slot 8. The hook portion 12 is formed by shearing and depressing a portion of the body member 4 from the underside thereof so that the hook portion 12 may engage with the slot 11 when the opposite portions 13 and 14 of the member 4 are manually moved toward one another.

It will be seen from the foregoing description that my improved arch support is substantially flat when it is delivered from the forming dies.

In order to provide a substantially strong, yet resilient arch in the member 4, the portions 13 and 14 thereof must be moved toward one another and the hook 12 engaged with the slot 11, the portion 13 overlapping the portion 14 at points adjacent the slot 8. This operation is done manually and the arch support will then assume the general shape shown in Figure 4. An inspection of Figure 4 will reveal that there are substantially two resilient arched portions 15 and 16 formed of the portions of the member 4 on either side of the slot 7. One of the advantages of dividing the arch support in this manner is to provide an adjustable support for both the inner and the outer longitudinal arch. It is well known in the

art that there is a vast difference between the inner and outer longitudinal arch in the feet of different people. Some patients suffer from weak inner longitudinal arches, which fact is evidenced by the turning in of the ankle and subsequent irregular wear upon the heel of the shoe worn by the patient. Other patients suffer from a weak outer longitudinal arch, though the inner arch may be normal. It is therefore of utmost importance to provide, as I have in my improved arch support, independent and adjustable supporting members for each of these two arches.

15 In inserting my improved arch support in the shoe, nails are driven through the openings 9 in the end 5, which end is disposed adjacent the heel 17 of the shoe, and inserting the upturned lugs 10 into the soft 20 inner sole 2. The lugs 10 will therefore preclude accidental lateral and longitudinal movement of the end 6 of the arch support.

From the foregoing description of the various parts of the device, the operation thereof may be readily understood. Ordinarily my arch supports may be shipped and conveyed to the shoe manufacturer or to the repair shop in a substantially flat condition as shown in Figure 1. It is at once evident 30 that this construction greatly facilitates packing and shipping, since the arch supports will occupy very little room and a great many may be packed one upon the other in a relatively small space.

35 When the arch support is ready to be applied to the shoe, the workman or manufacturer will manually move the portions 13 and 14 toward one another and lock the hook portion 12 in the slot 11. The portions 40 15 and 16 of the member 4 will immediately become arched and will remain so as long as the portions 13 and 14 overlap one another. This is apparently a buckling of the portions 15 and 16 of the member 4 due to 45 abnormal strain brought about by bringing the portions 13 and 14 out of their normal position. The arch support is then inserted between the insole and the outer sole 3, and the shoe is ready for the wearer.

50 In use, my arch support not only provides an independent resilient support for the in-

ner and outer longitudinal arch, but it also provides a self adjusting support for the transverse arch and the interior metatarsal arch. The peak of the arches of the portions 55 15 and 16, as indicated at 18, actually shift longitudinally of the member 4 when pressure is brought to bear upon the adjacent parts of the portions 15 and 16. It is therefore evident that if there is a tendency of 60 the foot to arch toward the heel that the peak 18 of the arches 15 and 16 will lie adjacent the heel, since the pressure will be somewhat increased at the forward end of the foot due to the relative position of the 65 bones and flesh of the foot. If the arch of the foot tends to lie adjacent the forward portion of the foot, then the peak 18 of the arched portion 15 and 16 will be substantially as shown in dotted lines in Figure 3, 70 i. e., the peak 18 always tends to assume a position in registration with the natural arch of the foot. In speaking of the arch, I have reference to the general arch of the entire bottom of the foot which might be considered the combination of the interior and 75 outer longitudinal arch.

I claim:

1. A device of the character described comprising a substantially flat resilient 80 metal member having an elongated opening therethrough, a slot extending longitudinally of said member from the edge of said member at one end to and communicating with the opening at its other end, whereby 85 the portions of said member adjacent said slot may be overlapped to cause said member to arch intermediate its length.

2. A device of the character described comprising a substantially flat resilient 90 metal member having an elongated opening therethrough, a slot extending longitudinally of said member from the edge of said member at one end, and communicating with the elongated opening at its other end, 95 whereby the portions of said member adjacent said slot may be overlapped to cause said member to arch intermediate its length, and means for locking said overlapped portions of said member against movement 100 apart from one another.

ISIDOR SOMMERFIELD.

,
